US00D663313S

(12) **United States Design Patent**
David et al.

(10) **Patent No.:** **US D663,313 S**
(45) **Date of Patent:** **** Jul. 10, 2012**

(54) **DISPLAY SCREEN WITH GRAPHICAL USER INTERFACE**

(75) Inventors: **Darren David**, San Francisco, CA (US); **Joshua Santangelo**, Seattle, WA (US); **Luis Eduardo Cabrerra-Condon**, Bothell, WA (US); **John E. Inman**, Duvall, WA (US)

(73) Assignee: **Microsoft Corporation**, Redmond, WA (US)

(**) Term: **14 Years**

(21) Appl. No.: **29/382,508**

(22) Filed: **Jan. 4, 2011**

(51) **LOC (9) Cl.** **32-00**

(52) **U.S. Cl.** **D14/487; D14/493**

(58) **Field of Classification Search** **D14/485-495; 715/700-867, 973-977**

See application file for complete search history.

(57) **CLAIM**

The ornamental design for a display screen with graphical user interface, as shown and described.

DESCRIPTION

The FIGURE is a front view of a display screen with graphical user interface showing the new design.

The broken line showings of the display screen and the images within the overlapping square regions are for environmental purposes only and form no part of the claimed design.

1 Claim, 1 Drawing Sheet
